UNITED STATES PATENT OFFICE.

BIRDORA H. WHITE, OF CHICAGO, ILLINOIS.

BUCKLE OR CLAMP.

Application filed April 3, 1920. Serial No. 370,962.

To all whom it may concern:

Be it known that I, BIRDORA H. WHITE, a citizen of the United States, residing at Chicago, in the county of Cook and State of Illinois, have invented new and useful Improvements in Buckles or Clamps, of which the following is a full, clear, and exact description.

My invention relates to buckles or clamps for supporting garments and particularly to the buckles or clamps described and illustrated in the pending applications for Letters Patent to the United States, filed by me February 28th, 1920, Serial No. 361,964.

The object of my invention is to improve the aforesaid buckle so that the cross-bars of the clamping member thereof can be separated or expanded at one end to permit of the introduction of the selvage edge of the supporting strap, between them, substantially as hereinafter fully described and as particularly pointed out in the claims.

In the drawings:

Figure 1 is a front view of my improved buckle showing it attached to the broken away portion of a strap.

Figure 2 is a vertical section taken on dotted line 2, 2, Figure 1.

Figure 3 is a perspective view of the same. The buckle to which my improvements are applied is, preferably, constructed the same as that described and illustrated in my aforesaid pending application for patent, but it will be apparent that in so far as the objects to be accomplished by said improvements, are concerned, it can be used just as well in buckle construction similar to those described and illustrated in my pending applications for Letters Patent to the United States, filed December 26, 1919, Serial No. 347,256.

My improved buckle comprises two members, one of which consists of an inverted U-shaped form, the horizontal bar 5 of which has its ends extending vertically downward to form parallel guides 6, 6, the lower ends of which are bent horizontally away from each other for a corresponding distance to form the lower bends 7, 7, of hooks. The remainder of the construction of these hooks is made by bending the outer ends of the bends 7, 7, upwards, to form upright portions 8, that are substantially parallel to the lower portions of the guides 6, 6. The upper ends of these portions 8, terminate below the center of length of the guides 6, and

are bent forward to form guards 9, 9, that extend to the vertical transverse plane of the bar 5 and guides 6, 6, and are then bent toward each other and looped to form terminal eyes 10, 10. The bends 7, 7, are preferably, curved rearwardly so as to conform to the curvature of the form of the body of the wearer against which they are designed to bear, and the terminals 10, 10, of these hooks are provided with eyes so as to prevent tearing the fabric and to facilitate the passage of the same past said terminals which said fabric would otherwise do if the terminals ended by abruptly cutting off the same.

The other member of said buckle comprises a clamp that is, preferably made of a single piece of wire and consists of a substantially straight horizontally disposed cross-bar 11, which at one end is coiled around one of the uprights 6 of the supporting-frame, to form an eye 13, that is slideable thereon, and extends from thence to the other upright 6 around which latter it is loosely coiled to form a tube 12 that surrounds and slides up and down upon the other guide 6. From the upper end of the tube 12, the wire extends in a direction substantially parallel to the cross-bar 11 to provide a cross-bar 14, and the end of this cross-bar 14 opposite tube 12 is loosely coiled around the opposite guide, 6, to form an eye 15 that is likewise slideable on said guide. The two eyes, 13 and 15, constitute a tube 16 similar to tube 12, and facilitate the upward and downward movement of the clamp on the supporting-frame. When the thickened end of strap A is threaded between the cross-bars of the clamp, the ends of the latter terminating in eyes 13 and 15, respectively, are separated further apart, substantially as shown in dotted lines in Figure 1, and provide a wider space for said thickened ends of the strap to be inserted between the cross-bars, which, if said bars were not separable in this manner would render the insertion of the thickened end of said strap A a very difficult thing to do.

The making of the cross-bars separable in the manner above explained, permits the strap to be held between the cross-bars 14 and 11 in a much more satisfactory manner, especially if the lower cross-bar is provided with an upward offset portion 16 between its ends. This could not be done were the cross-bar not separable.

In operation the lower end of strap A is first passed under and around the upper cross-bar 14 of the clamp, then back between said cross-bar 14 and cross-bar 5 of the supporting-frame, and then around the latter and down in front of cross-bar 14 and between the same and cross-bar 16 of the clamp. When any weight is put upon the hooks of the supporting-frame it will be drawn downwards and the fabric or strap will be clamped between the cross-bar 14 of the clamp and the horizontal bar 5 of the supporting frame. The operation of the buckle in other respects is the same as that described and claimed in my aforesaid applications.

What I claim as new is:

1. A buckle comprising an inverted U-shaped supporting-frame made of one continuous piece of wire its ends bent downwards to form parallel portions and having the lower ends of said parallel portions bent laterally away from each other and formed into hooks, and a clamping member consisting of a lower and an upper horizontal cross-bar connected at their ends by resilient tubular guides, one of which is divided mediate its ends, and said guides being slidably mounted on the parallel portions of said supporting-frame, said clamping member also being made of a continuous piece of wire and the guides of several coils.
2. A buckle comprising an inverted U-shaped supporting-frame consisting of a cross-bar the ends of which are bent downwards substantially parallel to each other and have their lower ends bent laterally away from each other and formed into hooks, and a clamping member consisting of a lower and an upper horizontal cross-bar connected at one end by a resilient tubular guide that is slidably mounted on one of the parallel portions of the supporting-frame, and having their opposite ends separated and formed into eyes that are slidably mounted upon the other parallel portion of said frame.
3. A buckle comprising an inverted U-shaped supporting-frame consisting of a cross-bar the ends of which are bent downwards substantially parallel to each other and have their lower ends bent laterally away from each other and formed into hooks, and a clamping member consisting of a lower and an upper horizontal cross-bar one of which is offset toward the other, and which are connected at one end by a resilient tubular guide that is slidably mounted on one of the parallel portions of the supporting-frame and have their opposite ends separated and formed into eyes that are slidably mounted upon the other parallel portion of said frame.

4. A buckle including an inverted U-shaped frame comprising a cross-bar the ends of which are bent downwards substantially parallel to each other and have their lower ends formed to attach to a garment, and a clamping member comprising a lower and an upper horizontal cross-bar and resilient means integral with the ends of said lower and upper horizontal bars and slidably mounted on one of said parallel frame portions, the free ends of said horizontal bars being formed with eyes slideable on the other of said parallel frame portions.

5. In a fastener, the combination with a U-shaped member, of a resilient member slidably mounted upon said U-shaped member and having its ends coiled about one leg of the U-shaped member and its middle coiled about the other leg.

6. In a fastener, the combination with a U-shaped member, of a resilient member having its middle coiled about one leg of the U-shaped member and shank portions substantially in the plane of the U-shaped member, terminating in coils about the other leg of the U-shaped member, said resilient member being slideable upon said U-shaped member.

7. A buckle comprising a U-shaped member having the parallel sides thereof bent laterally away from each other and terminating in eyes, and a resilient member slidably mounted upon said U-shaped member and having its ends coiled about one side of said U-shaped member and its middle coiled about the other side of said U-shaped member.

8. A buckle comprising a U-shaped member having the parallel sides thereof bent laterally away from each other and formed into hooks, and a resilient clamping member having its middle coiled about one side of said U-shaped member and shank portions substantially in the plane of the U-shaped member, terminating in coils about the other side of said U-shaped member, said clamping member being slideable upon said U-shaped member.

9. In a fastener, the combination with a U-shaped member, of a resilient member having portions coiled about the legs of the U-shaped member, and shank portions substantially in the plane of the U-shaped member, one of said shank portions being bent toward the other shank portion, said resilient member being slideable upon said U-shaped member.

In witness whereof, I have hereunto set my hand this 20th day of March, 1920.

BIRDORA H. WHITE.
